UNITED STATES PATENT OFFICE.

FRANK WYATT, OF HOXIE, KANSAS.

STACKER.

SPECIFICATION forming part of Letters Patent No. 738,390, dated September 8, 1903.

Application filed April 6, 1903. Serial No. 151,360. (No model.)

To all whom it may concern:

Be it known that I, FRANK WYATT, a citizen of the United States, residing at Hoxie, in the county of Sheridan and State of Kansas, have invented certain new and useful Improvements in Stackers, of which the following is a specification.

This invention belongs to the variety of machines for stacking hay, straw, or the like in the field when reaping the harvest. It is customary to gather the grain into sheaves, bundles, or shocks and to convey the latter to a selected spot to be formed in a pile or stack. This machine engages with said bundles or shocks and deposits same upon the stack in the formation of same.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view of a stacker embodying the invention. Fig. 2 is a side elevation thereof. Fig. 3 is a plan section about on the line X X of Fig. 2, the seat and operating-levers being in full.

Corresponding and like parts are referred to in the following description and indicated in all the views of the drawings by the same reference characters.

The frame comprises side bars 1, forwardly diverged, and transverse connecting-bars 2 and 3. The front axle 4 is journaled in bearings applied to the forward ends of bars 1, and the ground-wheels 5 are secured thereto in the accustomed way to compel rotation of axle 4 when the stacker is advanced. The rear end of the frame is supported by means of caster-wheel 6.

A draft-beam 7 is secured to the frame, near its rear end, and is provided with swingletrees 8, to which the animals are hitched, the breast-chains 9 being applied to bars 1, near their forward ends, to be connected with the collars of the harness in the usual way. The seat 10 is secured to the rear portion of the

frame, and the operating-levers are within convenient reach thereof.

Standards 11 are secured at their lower ends 55 to the frame, about midway of its front and rear ends, and are connected at their upper ends by transverse rods 12 and 13 and are braced fore and aft by stays 14 and 15. Direction-pulleys 16 are applied to the ends of 60 rod 13, and rod 12 forms a pivotal support for the beam or lever 17, carrying fork 18, pivoted thereto. Beam 17 comprises similarly-formed side pieces, each consisting of bar 19 and braces 20 and 21, secured at their outer end 65 to the extremities of bar 19 and upwardly and inwardly inclined and transversely bored to receive rod 12 at their point of crossing. The side pieces are forwardly diverged in conformity to the inclination of bars 1, the several parts 19 and 21 meeting at their rear ends and provided with eye 22, to which the operating cord or cable 23 is attached, same passing beneath direction-pulley 24, applied centrally to bar 3, thence forward and attached 75 to drum or spool 25, loosely mounted upon axle 4 and provided with ratchet-wheel 26 for coöperation with pawl 27, whereby said drum is prevented from backward rotation when rotated forward to wind up cord or rope 80 23 to elevate fork 18. Pawl 27 is connected by rod 28, with hand-lever 29 near the rear end of the machine and within convenient reach of the driver's seat. Drum or spool 25 is provided at one end with half-clutch 30 for 85 coöperation with clutch member 31, slidably mounted on axle 4, but connected for rotation therewith. Spring 32 is confined between clutch member 31 and stop 33, secured to axle 4, so as to hold parts 30 and 31 in engagement when it is required to have drum 25 rotate with axle 4, so as to wind up rope or cord 23 to elevate the fork and the load carried thereby. Skipper-lever 34, of approximately bell-crank form, is fulcrumed, at 90 the elbow to cross-bar 2 and has one member in engagement with clutch member 31 and the other member connected by rod 35 with lever 36, pivoted to the frame and extended within convenient reach of the driver's seat. 100

The fork 18 is substantially of ordinary construction, comprising head 37, teeth 38, extended forward from head 37, and supporting-frame 39 in line with head 37 and at a

right angle to the plane of teeth 38, so as to project in an approximately vertical direction to prevent rearward displacement of the shock or bundles when the machine is advanced to engage with same. Fork 18 is pivoted or otherwise loosely connected to the front end of beam 17 and is held in the required position by means of cords or ropes 40, connected at their front ends to the upper end of frame 39 and passed over pulleys 16, thence rearward and downward and attached to operating-lever 41, pivoted to the rear portion of the frame and readily accessible from the driver's seat.

15 In the practical operation of the machine the draft-animals are hitched to the swing-trees 8 and breast-chains 9 in the usual manner, and the machine is advanced with the fork lowered, so as to engage with the shock or bundle, after which lever 36 is operated to throw drum or spool 25 into clutched engagement with axle 4. As the machine is advanced toward the stack after the load has been received upon the fork spool or drum 25 rotates with axle 4 and winds up cord or rope 23, thereby elevating the fork and the load. After the load has reached the required elevation lever 29 is operated to permit pawl 27 to engage with the teeth of ratchet-wheel 26, so as to prevent backward rotation of the spool or drum after the latter has been unclutched from axle 4. Obviously the load may be held in suspension until the frame is properly positioned, after which lever 41 is operated to release fork 18 and permit it to tilt under the weight of the load, which is discharged upon the stack or pile, as will be readily comprehended. Upon operating lever 29 spool or drum 25 is released, thereby permitting the fork to descend and assume a

normal position preliminary to receiving the next shock or bundle to be deposited upon the stack, the operation being substantially the same as that hereinbefore described.

Having thus described the invention, what is claimed as new is—

1. In a stacker, a beam comprising side pieces rearwardly converged, each side piece comprising a straight bar and oppositely-inclined bars forming braces, a fork pivotally connected to the diverged ends of said side pieces, and operating means connected to the converged elements of the beam, substantially as described.

2. In combination, a frame comprising forwardly-diverged side bars, standards rising from said side bars intermediate of their ends, braces between the upper ends of said standards and the extremities of the side bars, a beam comprising forwardly-diverged side pieces, each comprising a bar and oppositely-inclined brace-bars pivoted at their meeting ends to said standards, a fork pivotally connected to the front ends of said side pieces, a drive-axle, a drum loosely mounted thereon, a clutch for throwing said drum into and out of engagement with the axle, an operating-lever for controlling said clutch, a ratchet and pawl for preventing backward rotation of the drum, an operating-lever for controlling the pawl, a cord or rope for controlling the position of the fork, and a lever having said cord or rope connected therewith, substantially as set forth.

In testimony whereof I have affixed my signature in presence of two witnesses.

FRANK WYATT. [L. S.]
